UNITED STATES PATENT OFFICE.

MALCOLM RIARSON KESTER, OF CHICAGO, ILLINOIS.

CAM-HOLDER FRAME.

1,408,809.

Specification of Letters Patent.

Patented Mar. 7, 1922.

Application filed November 22, 1920. Serial No. 425,863.

To all whom it may concern:

Be it known that I, MALCOLM R. KESTER, a citizen of the United States, residing at Chicago, in the county of Cook and State 5 of Illinois, have invented a new and Improved Cam-Holder Frame, of which the following is a specification.

This invention has reference to passenger and freight elevator equipments and particularly to the installing, equipment and adjusting of the cam or cams that actuate the limit switches, and the speed controlling or "gradient" switches in places where such switches are used and form or constitute an 15 integral part of the electrical devices and their correlation to the elevator mechanism, and my said invention more specifically provides a means, in the nature of an improved frame structure upon which to mount, hold 20 and adjust the cam or cams that coordinate the limit switches and such other switches which function to interrupt the travel or speed of the elevator car and regulate its gradient with reference and conformity to 25 its properly approaching and stopping at the floor levels or at the predetermined points at the top or bottom of the hatchway or at the final limits of the travel of the elevator car.

30 Primarily, my invention seeks to provide a cam holder frame of the general character mentioned that can be installed at a relatively small expense, is positive in its action and in which the adjusting features are 35 especially designed for accurately placing the cams, vertically or laterally, with respect to the car, to suit the desired requirements for coengaging the switch stops or members disposed within the path of the cam travel 40 and in which the parts are capable of being easily and expeditiously adjusted for accurate timing contact with the stops, as conditions may require the cams to be projected from the elevator car.

45 With other objects, purposes and special application of my invention in view, which will be hereinafter fully outlined, my said invention is fully stated in the following detailed description and specifically mentioned in the appended claims, reference being had to the accompanying drawings, in which:

50 Figure 1 is a diagrammatic side elevation of an elevator car with my cam holder frame attached and a number of cam engaged

limit switches located at or near the upper and lower limits, respectively, of the car travel.

Figure 2 is a perspective view of a preferred construction of cam and holding frame 60 members cooperative therewith, the cam proper being shown as composed of a plurality of switch roller contacting members.

Figure 3 is a similar view of a modified form of cam and holder frame construction 65 hereinafter specifically referred to.

Figure 4 is a longitudinal section of one half of the cam and holder frame construction shown in Figure 2.

Figure 5 is a horizontal section thereof 70 taken on the line 5—5 on Figure 4.

Figure 6 is a perspective view of the adjustable angled frame on which the cam shoes or contact members are mounted and which is adapted for adjustable connection 75 with anchor links hereinafter referred to.

Figure 7 is a similar view of the angle bar 80 holder frame that constitutes a part of the modified arrangement of my invention shown in Figure 3.

Figures 8 and 9 are perspective views of the retainer straps hereinafter specifically mentioned.

Figure 10 is a detail perspective view of one of the anchor links hereinafter specifically mentioned.

Referring now to the details of the drawings, in which like numerals and characters indicate like parts in all of the figures, although I have illustrated my invention as 90 showing the same applied to an elevator cage and cooperative with roller controls for the limit switches located above and below the limit of travel of the said cage, it is to be understood my invention is not restricted in 95 its use to elevator apparatus, such as indicated, but may be utilized wherever it may be applicable, that is, where careful adjustment of cam shoes for engaging cut out switches or other like elements is required, 100 since the primary object of my invention is to provide a holder frame on which to mount and adjustably affix a cam or cams, the holder frame being especially designed so that the combination of the several elements 105 that constitute the frame, make the said holder frame adaptable to all needs or requirements of gradient switches and limit switch installation.

Referring now more particularly to Fig. 110

- ures 1, 3, 4 and 5 of the drawings, the holder frame therein shown can be readily and easily affixed to any quarter or section of the elevator car, and when so required, the said frame can be rigged in any suitable position at the top or bottom of hatchways, and in either fitting to allow for securing the cam or cams to the hatchway at the desired adjustments required.
- 10 The holder frame in the complete make-up, as shown in Figures 1, 3, 4 and 5, comprises an angled bar 1, one face or leg 10 of which has two sets of aligning elongated slots 20, one set (two) of such slots being at each end of the leg 10, and at each end of the said leg 10 of the angle bar 1, is located a small angle bracket 3, which, in practice, may be an integral part of the bar 1 riveted or otherwise made fast thereto, and each of 15 the brackets 3 has a centrally located aperture 30, the reason for which will presently appear.
- 15 The side face or leg of the bracket 1 has an elongated slot 4 at each end thereof and a number of apertures 40 located in longitudinal alignment between the slots 4, as is clearly shown in the drawings.
- 20 25 30 35 40 45 50 55 60 65

In the preferred construction, Figures 1, 2, 4 and 5, two cams or switch roller contacting shoes are shown as mounted on the angle bracket 1 and the said arrangement of my invention, as shown in the aforesaid Figures 1, 2, 4 and 5, is more especially designed and provided in order that the upper cam section which coordinates and actuates the switch or switches in the top part or section of the hatchway, with reference to the top landing or limit of the car's travel upward, can be adjusted or readjusted independently of and without disturbing the lower cam section, and conversely, the lower cam section or member which coordinates and actuates the switch or switches in the bottom part or section of the hatchway with reference to the bottom landing or limit of the car's travel downwardly, can be adjusted or readjusted without interfering with or disturbing the upper cam section or member, hence either of the two cam sections may be independently shifted, up or down, in the manner presently explained, while leaving the other cam section or member intact.

Each cam section is fixed to its respective holder frame end by means of a square headed bolt 6, the head of which engages a countersunk notch 60, when the cam is of wood, to provide for the said bolt coming flush with the cam surface and thereby produce a smooth contacting surface through the full length of the cam face for engaging the roller contacts of the limit switches or cut outs.

Each cam section is connected to the holder frame portion 1 for longitudinal adjustment along the said frame portion 1 and

said adjustment of the cam is effected by an adjusting rod 14 whose inner end has an eye 15 through which the threaded shank 62 of the bolt 6 passes and which is held in operative connection with the said bolt shank by 70 nut and washer fittings 16, as shown.

The adjusting rod 14 has its threaded shank projected through the apertured end bracket 3 and the said rod may be readily shifted through the bracket to bring the 75 cam shoe to the desired longitudinal adjustment along the holder bracket 1 and held to its adjustment by adjusting nuts 17 and 18, which engage the rod 14 at each side of the bracket 3, as is best shown in Figure 4. 80

The means so far described, provide for adjusting the cam shoes or members along the angle bracket 1 of the holder frame, such adjusting means allowing for a final close or accurate setting of the cam shoes after the 85 holder frame shall have been primarily adjusted, either laterally or vertically with respect to the elevator car or hatchway with which my cam holder frame devices may be cooperatively combined. 90

For supporting the holder frame, also for connecting it with the specially designed primary anchor bracket, affixed to the elevator car or to the guide post, and for conveniently effecting both lateral and vertical 95 adjustment of the holder frame with respect to the car or hatchway and the coordinating parts, I provide a pair of what I term anchor links 19—19, one of which is shown in detail Figure 10, one of the said links being 100 provided for each end of the cam holding angle bar and positioned relatively, as shown in Figures 2 and 3, and rigged in the elongated apertrures 4 of the said angle bars, as best shown in Figures 6 and 7. 105

The links 19—19 are in the nature of a straight piece of suitable strap iron and each link has a shank or stem end that is provided with two holes 19^a and 19^b, which adapt the link for being secured to the specially designed anchor bracket 19^c by means of two tie bolts that pass or take through the holes 19^a and 19^b in the shank or stem end of the link 19 and through corresponding holes in the shank or stem end of the 110 aforesaid primary anchor brackets 19^c, which is especially provided for being affixed to the elevator car, the elevator guide post, or to the side of the hatchway according as the installation designed or lay out 115 120 may require.

The end or portion of the anchor link 19 opposite to the shank or stem end having the connecting holes 19^a and 19^b has an elongated slot 24 to provide for the reception of a 125 clamp bolt 25 which passes through the elongated slot 4 in the corresponding end of the side member of the bar 1 and through the slot 24 in the bracket or link member 19, a nut 26 engaging the threaded shank of the 130

bolt 25 tending to clamp the cam carrying member 1 to any of the vertical adjustments along the anchor links or brackets 19, it being understood that the bracket portion of the cam holder may be readily adjusted along the slotted anchor links 19 and made fast to the adjusted position by the same bolt 25 that secures the cam holder at its laterally adjusted positions.

10 To positively secure the cam holder or angle bar to any of its lateral adjustments with respect to the elevator car or hatchway, to which my cam holder frame may be applied, retainer devices are provided, the said 15 devices being in the nature of a pair of strap irons 28, one for each anchor link or bracket 19.

Each of the irons 28 is formed with a single aperture 29, at one end, for receiving a keeper bolt 31 that secures the said end of the iron 28 to the inner end of the bracket link 19, as is best shown in Figures 10 and 2, by reference to which it will also be observed that the other end of the retainer 25 member 28 has a series of closely arranged apertures 28^a, whereby to provide for passing the bolt 25 through any selected one of the apertures for securing the angle bar 1 at any of its adjustments laterally along the 30 link or bracket irons 19.

32—32 designate other retainers or strap irons, each of which is provided with apertures 33, at one end, for receiving a bolt 34 which also takes through one of the apertures in the side face or member of the angle bar 1, as is best shown in Figures 1 and 2, by reference to which and to Figure 4 it will also be seen the retainers 32 have a series of closely arranged apertures 35 at the outer 35 end, through any selected ones of which the bolts that secure the angle bar 1 and the anchor links or brackets 19, are passed when making the longitudinal adjustment of the said bar 1 with respect to the said links 19.

40 By reason of the peculiar arrangement of the parts so far described and as clearly shown in the drawings, a simple, easily applied and effective means is provided for adjusting the cam holder or angle frame 1 laterally to and from the car or the hatchway to which my holder frame is applied, and for locking the said holder bar 1 to its laterally adjusted positions along the anchor links or brackets 19 as against accidental displacement or becoming loosened 45 under ordinary usage of the holder frame.

Furthermore, the parts shown and so far described, also provide for effecting a primary adjustment of the cam carrying or 50 holder frame or bar 1 in the vertical direction of the elevator car or hatchway and along the anchor links or members 19 and also to hold the said bar securely locked to any of its vertical and lateral adjusted positions.

Thus, while a simple, convenient and readily manipulated means is provided for effecting the primary adjustment of the cam holder bar 1, a further or accurate adjustment of the cam shoes or members lengthwise of the bars, up or down, as conditions may make necessary, is also provided by the threaded rods that join with the outermost ones of the bolts secured to the cam member and which pass through the outermost ones 70 of the elongated slots 20 in the outer face of the bar 1, it being understood the adjustment of the screw rods is effected by the nuts 17 and 18 that engage the inner and outer faces of the apertured end brackets 3—3, as 80 is clearly shown in Figure 4.

In the modified showing of my invention, illustrated in Figures 3 and 7, the same basic arrangement of parts is embodied as appear in the preferred construction, the 85 said modified arrangement differing from the said preferred construction in that the angle bar 1 is provided with only one set (2) of elongated slots 20 for the reception of a pair of the adjusting bolts 6 that secure 90 a single section or cam shoe and, in this latter arrangement, the same means or parts is utilized for effecting the vertical and lateral adjustment of the frame 1 with its single cam section or shoe as is provided for 95 the same purpose for effecting the vertical and lateral adjustment of the angle bar 1 provided with the two cam sections or shoes.

From the foregoing description taken in connection with the drawings, the complete 100 construction, the manner of effecting the desired adjustment of the cams, with respect to the elevator car or hatchway, and the advantages of my invention will be readily apparent to those familiar with electrically 105 controlled elevator installation.

While the modified form of holder frame, shown in Figures 3 and 7, is more especially designed to be rigged or installed and used at the top and bottom of the hatchway, respectively, in places where the limit switch (or other switch) is located or installed on the elevator car, hence the obvious need or advantage of the two cam section holding frames shown in Figures 1, 2, 4 and 5 and 110 its installation, under conditions where stop motion or gradient switches are used, in connection with the final limit switches at the top and bottom of the hatchway, the obvious need of a one piece cam holder frame is also 115 apparent, when it is rigged at the top and bottom of the hatchway in cases where the limit switches, or other switches or cut outs are placed or installed directly on the elevator car.

125 Among other advantages, in the provision of a cam holder frame such as hereinbefore described and shown in the drawings, is that, when the two cam sections or shoe equipment is installed on the elevator car 130

and hence travels up and down therewith, the coordinating switches—limit, gradient, stop motion, automatic, and the like—must necessarily have a fixed position at the top 5 and bottom of the hatchway, respectively, and be located with reference to their particular function and purpose; conversely in case where the limit switch or other correlative switch is installed on the elevator car 10 and hence travels up and down therewith, the coordinating holder frame and its fixed cam must necessarily be rigged in a fixed position, respectively, at the top and bottom of the hatchway with reference to the position, function and purpose of the said cams.

The essential feature of my invention which should be here again stated, is the provision of a holder frame on which the cams have adjustment and means for adjusting the holder frame relatively to the elevator car or the hatchway, that remains the same in all cases of installation and methods of application.

My cam holder frame construction is such that in case it becomes necessary, for any reason, to readjust the cam or cams in order to make the cam contact with and actuate the switch or switches more suitable and precise, with reference to any drift, irregularity or changed condition of the holder frame itself, sequences or relationship involving the correlation between the moment of switch actuation; the brake action of the winding apparatus; and the gradient of the elevator car stoppage at the desired floor level, such cam readjustment may be had by a resetting of the holding frame or perhaps, if necessary, by simply turning back or loosening the nuts on the cam holding bolts 6 30 movable in the elongated slots 20, and the lock nuts 17 and 18 on the adjusting rods 14 that move through the apertured brackets 3, to thereby shift the cam or cams as desired, up or down, on the holder frame; adjust the 40 brakes, if need be, correct the electrical defects, if any, then try out and check up and in case the results are not right or do not suit or meet the desired requirements, repeat 45 or continue the adjustments as stated until 50 the particular parts involved or effected, coordinate the cam adjustment and reciprocal function to eventuate the desired gradient of the elevator car stoppage at the floor level or at any other predetermined 55 point above or below the said floor level at at the top and bottom landings.

When the cam action has been set aright and the other parts conform and accord with the gradient, stop motion or final limit of 60 the car's travel, up or down, then tighten up the adjusting rod lock nuts 17 and 18 and clamp the cam shoe or shoes firmly against the holder frame as hereinbefore outlined.

65 It is to be understood that in the construc-

tion, application and use of my invention, the exact dimensions, precise details of connection of the parts and the formation thereof as hereinbefore described, and shown in the accompanying drawings, may be further 70 modified or varied to suit the particular requirements in their installation without departing from the essential or basic feature of my invention as comes within the scope 75 of the appended claims.

What I claim is:

1. In an electrically propelled elevator installation, cam mechanism for engaging and controlling the action of the limit, electric circuit controlling devices, means for first 80 effecting an initial fixed position of the cam mechanism with respect to the circuit controlling devices, and other means for effecting a final adjustment of the cam shoes or members to provide for predetermined time 85 contacting of the cams with the said circuit controlling devices.

2. In an electrical power actuated elevator installation, the combination with a cut out switch; of a cam holding frame, the 90 said frame and the cut out switch having movement relatively to each other and means for adjusting the cam holder for positioning the cam for contacting with the cut out switch at predetermined points of 95 movement of the cam or switch relatively to each other.

3. In an electrical power actuated elevator installation, the combination with a cut out switch; of a cam holding frame, the 100 said frame and the cut out switch having movement relatively to each other and means for adjusting the cam holder for positioning the cam for contacting with the cut out switch at predetermined points of 105 movement of the cam or switch relatively to each other, the said means including devices for setting the cam holder in a relatively fixed position for engaging the cam with the switch and other devices for adjusting the cam in its position on the holder for timing the contacting of the said cam and the aforesaid switch.

4. In an electrically operated elevator installation, a cut out switch in the power conveying circuit, and a cam having a shoe for engaging the switch to interrupt the car moving power means and for effecting a relatively fixed adjustment of the cam and the switch and other means movable with the cam for effecting adjustment of the cam shoe, up or down, for timing the contacting of the cam shoe and the switch.

5. In an electrically operated elevator installation, the combination with a car, a 125 cam device movable with the car, a limit cut out switch in the electric operating circuit, the said cam device including a cam holding frame secured to and laterally adjustable with respect to the car, means for effecting 130

such adjustment of the cam holding frame, the said means comprising anchor links and primary anchor brackets that are rigged to suit the installation requirements secured to 5 and projected horizontally from the car, a cam holder frame and devices for adjustably mounting the said holder frame for slidably engaging the anchor links and securing the same along the said links for the purpose 10 specified.

6. In an electrically operated elevator installation, the combination with a car, a cam device movable with the car, a limit cut out switch in the electric operating circuit, the said cam device including a cam holding frame secured to and laterally adjustable with respect to the car, means for effecting such adjustment of the cam holding frame, the said means comprising anchor links secured to and projected horizontally 20 from the car, a cam holder frame and devices for adjustably mounting the said holder frame for slidably engaging the anchor links and primary anchor brackets 25 that are rigged to suit the installation requirements, and securing the same along the said links, the said devices comprising an elongated slot formed lengthwise in each of the anchor links, bolts that take through the cam holder frame and the aforesaid slots in the anchor links and a retainer link pivotally secured to each of the anchor links and having a series of apertures, through 30 selected ones of which the bolts that secure 35 the cam frame and engage the slots in the anchor links, are adapted to pass, when locking the cam holder to its lateral adjustments with respect to the car.

7. In an electrically operated elevator installation, the combination with a normally closed circuit controlled switch that constitutes a part of the installation and the car; of a switch engaging cam, a holder therefor, means for mounting the frame on 40 the car, said means including devices for effecting adjustment of the frame laterally with respect to the car, said cam comprising at least one switch contacting shoe, means mounted upon and movable with the holder 45 for effecting longitudinal adjustment of the cam shoe, up or down, along the frame whereby to set the cam shoe for engaging the switch at predetermined points in the 50 travel of the cage up or down.

8. In an electrically operated elevator installation, the combination with the elevator and a switch in the electric transmission circuit for effecting either the up or down limits or intermediate stoppages of 55 the car; of a cam holding frame, means for mounting the frame on the car to move therewith and for effecting lateral adjustments of the said frame relatively to the car, a cam shoe mounted on the frame for 60 engaging the electrical cut out switch and

means for effecting adjustment of the shoe vertically with respect to the holding frame and the car.

9. In an electrically operated elevator installation, the combination with the elevator and a switch in the electric transmission circuit for effecting the limits of intermediate stoppages of the car; of a cam holding frame, means for mounting the frame on the car to move therewith and for effecting 70 lateral adjustments of the said frame relatively to the car, a cam shoe mounted on the frame for engaging the electrical cut out switch and means for effecting adjustment of the shoe vertically with respect to the 75 holding frame and the car, the said means comprising an angle bar, one member of which has elongated slots, bolts engaging the cam shoe that pass through the slots in the angle bar and draw rods mounted on 80 the angle frame connecting the shoe engaged bolt and means for effecting adjustment of the draw rod for sliding the shoe or shoe members lengthwise up or down along the slotted members of the angle bar. 85

10. In an electrically operated elevator installation, the combination with a circuit breaking switch and the car; of a switch engaging cam mechanism movable with the car, said cam mechanism including a cam 90 holder frame, means for mounting the said frame on the car to move therewith and effect lateral adjustment thereof relatively to the car, the said means for mounting the cam frame including anchor links projected 95 laterally from the car, the holder including an angle bar, one face of which carries the cam shoe, the other face or arm of which is slotted longitudinally, at its opposite ends, keeper bolts that engage the slots in the 100 angle bar and the anchor links, whereby to provide for shifting the holder frame vertically with respect to the car. 105

11. In an electrically operated elevator installation, the combination with a circuit 110 breaking switch and the car; of a switch engaging cam mechanism movable with the car, said cam mechanism including a cam holder frame, means for mounting the said frame on the car to move therewith and 115 effect lateral adjustment thereof relatively to the car, the said means for mounting the cam frame including anchor links projected laterally from the car, the holder including an angle bar, one face of which carries the 120 cam shoe the other face or arm of which is slotted longitudinally, at its opposite ends, keeper bolts that engage the slots in the angle bar and the anchor links, whereby to provide for shifting the holder frame vertically with respect to the car, and means 125 carried by the angle bar for interlockably engaging the aforesaid keeper bolts for locking the cam carrying angle bar to its vertical adjustments on the anchor links. 130

12. In an electrically operated elevator installation, the combination with a circuit breaking switch and the car; of a switch engaging cam mechanism movable with the car, said cam mechanism including a cam holder frame, means for mounting the said frame on the car to move therewith and effect lateral adjustment thereof relatively to the car, the said means for mounting the cam frame including anchor links projected laterally from the car, the holder including an angle bar, one face of which carries the cam shoe, the other face or arm of which is slotted longitudinally, at its opposite ends, keeper bolts that engage the slots in the

angle bar and the anchor links, whereby to provide for shifting the holder frame vertically with respect to the car, and means carried by the angle bar for interlockably engaging the aforesaid keeper bolts for locking the cam carrying angle bar to its vertical adjustments on the anchor links, the said means comprising retainer arms pivotally secured, at one end, on the angle bar and having its other end formed with apertures 20 adapted for being selectively brought into position for being engaged by the keeper bolts. 25

MALCOLM RIARSON KESTER.
